UNITED STATES PATENT OFFICE.

JESSE A. B. SMITH, OF STAMFORD, CONNECTICUT, ASSIGNOR TO UNDERWOOD ELLIOTT FISHER COMPANY, OF NEW YORK, N. Y., A CORPORATION OF DELAWARE.

TYPEWRITING MACHINE.

Application filed May 12, 1928. Serial No. 108,451.

This invention relates to fan-fold typewriting machines of the kind disclosed in the patent to George W. Renz, dated July 29, 1924, No. 1,503,064, in which two fan-fold web-forms are interchangeably employed in connection with a double carbon-carrier, that is, a set of two carbon-carriers mounted in superposed relation on a carriage, and movable as a unit toward and from the platen, each carrying carbon-sheets interleaved with its web-form.

When the lower web-form of a set is in use, the leading end of the idle upper web-form can be readily folded back over the upper carbon-carrier out of the way; but it is sometimes difficult and tedious for the unskilled operator to thread the leading free end of the lower web compactly back through the lower carbon-carrier to the inactive position, when the upper web-form is to be used.

An object of the present invention is to provide an improved construction whereby, when it is desired to employ only the upper web, the operator may withdraw the lower web from the platen and fold or turn it back over its carbon-carrier out of the way easily and in a minimum of time.

At the rear of the machine the webs hang in contact one with the other, and in this relation the idle web, through friction, tends to interfere with the feeding of the active web into the machine. Moreover, when the lower web is not in use and is folded back to the inactive position, its free end will in some instances strike the hanging upper web at each back movement of the carbon-carrier, when stripping the carbons prior to starting the typing of a new form; and this contact of the end of the lower web with the incoming upper web also impedes or interferes with the feeding action of the machine, causing an objectionable drag on the platen.

Another feature of the present invention is the provision at the rear of the machine of a drop or chute to receive the turned back free end of the lower work-form, so that it will not come in contact with the active upper web nor interfere with the feeding thereof into the machine.

There is herein disclosed a novel construction whereby the free end of the lower work-form of a set may be expeditiously deposited on and over its carbon-carrier, to permit the upper web-form to be typed upon,

and further to provide, at the rear of the machine, a drop to receive the free end of the lower web-form when the carbon-carrier is forced or moved backwardly when stripping the carbons prior to beginning a new 60 typing operation on the active web.

A feature of the invention resides in the construction of the double carbon-carrier, whereby the operator may move the upper carbon-carrier out of the way so that the 65 lower work-web may be folded back when the upper web is to be typed upon, the carriers being separable, that is, the upper carrier may be lifted bodily from the supports, or it may be tilted or swung upwardly 70 on two of its supporting posts which are provided with hooks to retain and guide the carrier as it is being lowered to the normal horizontal position.

A further feature of the invention is the 75 provision of an adjustable rearwardly-extending bracket carried on the work-frame at the rear of the machine and which is constituted by parallel backwardly-ranging arms connected by widely-spaced guide-bars 80 over which the work-webs are fed into the machine, the space between these work-webs forming a drop for the backturned end of the lower web when the upper web is in use.

The manner of mounting the upper carbon-carrier permits its quick removal from the machine with its work-web and interleaved carbons and the substitution of another work-web in its stead when desired.

Other features and advantages will hereinafter appear.

In the accompanying drawings, Figure 1 is a central longitudinal sectional elevation of the machine showing a set of relatively separable superposed carbon-carriers and an adjustable bracket for guiding and spacing the work-webs.

Figure 2 is a fragmentary plan view of the machine as shown in Figure 1.

Figure 3 is a front elevation of the set of carbon-carriers and its supporting carriage.

Figure 4 is a detail perspective of the carbon-carriers removed from the carriage showing the upper carrier tilted upwardly to provide space or clearance for the lower work-web to be folded back to the inactive position prior to advancing the upper web toward and around the platen to the typing position.

Referring to the drawings, the usual platen

5 is mounted in a carriage 6 to the rear of which is a work-frame 7. The usual feed-rolls 8 assist the platen in feeding one of the sets of work-webs 9, 9^a around the platen in the operation of the machine.

6 Mounted on the work-frame 7 is a carriage 10, including a bed-plate 11, carrying rollers 12 which have rolling contact with supporting rails 13 on the work-frame. On the 10 carriage is mounted a set of two superposed carbon-carriers 14 and 15, each including a base-plate 16 and 17 respectively, on which are carried stepped blocks 18 and 19, arranged in pairs and which support the 15 usual carbon-blades 20, to which the usual carbon-sheets 21 are connected.

7 The base-plate 16 of the lower carbon-carrier 14 is detachably connected to the bed-plate 11 of the carriage in the usual well-known manner as at 22 and carries, preferably near its corners, at opposite sides of the machine, vertical posts or supports 23 and 24 also arranged in pairs. The posts 23 are reduced at the top to form pins 25 which pass freely through apertures 26 in the base-plate 17 of the upper carbon-carrier 15. The posts 24 are also reduced at the top but are extended to form hooks or curved portions 27 which are received freely in apertures 28 also in the base-plate 17. The reduced pins 25 and hooks 27 provide shoulders 29 and 30 on the respective pairs of posts to support the upper carbon-carrier in the normal horizontal position. In 35 the preferred operation, to facilitate providing a space between the upper and lower carbon-carriers for turning back the lower work-web on its carrier, the upper carrier is tilted or swung upwardly by pressing down 40 on the handle 31, the shoulders 30 providing the fulcrum on which it swings. The hooks 27, being curved substantially on the arc of the swing, act to prevent said movement or displacement of the upraised carrier, so that 45 when said carrier is lowered, the pins 25 on posts 28 will be in registration with the apertures 26.

8 Of course, as hereinbefore stated, the upper carbon-carrier, with its web, may be 50 lifted bodily from the machine or its supporting posts if desired, to provide the desired space for the backturn of the lower web but this would require more time and labor in replacing it on the pins and hooks and is not desirable, as speed is a desideratum.

9 Mounted at the rear of the machine, in 55 vertically-arranged posts on the work-frame 7, is a cross-bar or guide 33 over which the lower web is drawn into the machine and on which are the usual centering guides 34 for centering the web in its travel to the platen.

10 Supported on the extended ends of the bar or guide 33, are backwardly-directed 60 arms 35 connected at their free ends by a

cross-bar or guide 36 over which the upper web-form is drawn into the machine and on which are centering guides 37 similar to the guides 34. These guides are all adjustable on their respective bars and are held in a 70 desired position by screws 38 or the like.

11 The arms 35 and cross-bar 36 collectively constitute a bracket or guide for supporting and guiding the upper work-form, said bracket or guide being adjustably mounted 75 on the guide-bar 33 and held at a desired angle to the horizontal by set screws 39 or the like. The guide-bars 33 and 36 are preferably widely separated. The space between the hanging lower and upper work-webs constitutes a drop 40 to receive the backturned free end 9^b of said lower web when the carbon-carriers are moved back by forcing the usual push-bar, indicated at 41, rearwardly of the machine when stripping the carbons in the upper work-web 80 prior to typing a new form.

12 The advantages resulting from the use of the machine as above described will readily be apparent. As pointed out above, the operator has but to tilt the upper carrier on the curved hooks or hinge-pins 27 to provide an enlarged space wherein to fold back the free leading or forward ends of the lower group of worksheets, thereby avoiding the 90 painstaking and time-consuming operation of threading said leading or forward ends through the narrow space between the superposed carbon-carriers. These reversely-turned free ends are thrown back to drop 100 into the chute or drop 40, the weight of these free ends tending to keep the forwardly-extending loop shown at 9 of minimum size, thereby preventing curling and creasing of the sheets at this loop as the carrier reaches the limit of its movement toward the platen. The reversed free ends will tend to 105 occupy the space between the groups of sheets 9 and 9^a, shown at the left of Figure 1, out of contact with said sheets, particularly with sheets 9^a. This is an important 110 advantage, since there is relative motion between the free ends 9^b and sheets 9^a during the reciprocating motion of the carbon-carriers, and if frictional contact between them 115 were not prevented, curling, snarling and bunching of the free ends would result.

13 Variations may be resorted to within the scope of the invention and portions of the improvements may be used without others. 120

Having thus described my invention, I claim:

14 1. In a typewriting machine of the class described, a set of relatively separable carbon-carriers arranged one over the other, 125 and means on the lower carrier for supporting the upper one, said supporting means being provided with extensions to engage the upper carrier to permit tilting movement thereof on said supporting means. 130

2. In a typewriting machine of the class described, a set of relatively separable carbon-carriers arranged in superposed relation, and a plurality of posts on the lower carrier, said posts having shoulders to support the upper carrier, some of said posts having hooks to coact with the upper carrier and permit tilting movement thereof.
3. In a typewriting machine of the class described, a set of superposed relatively separable carbon-carriers, each carrier including a base-plate and a set of carbon-carrying blades, posts arranged on the base-plate of the lower carrier, said posts having reduced top extensions and shoulders, some of said extensions being prolonged and curved, the base-plate of the upper carrier being provided with apertures to loosely receive said extensions, and a handle carried by the upper carrier.
4. In a typewriting machine of the class described, a set of superposed relatively separable carbon-carriers, each carrier including a base-plate and a set of carbon-carrying blades, posts carried by and arranged in pairs at opposite sides of the lower base-plate, said posts having shoulders and extensions passing through apertures in the upper base-plate, the extensions of the posts at one side of the carrier being prolonged and curved outwardly, and a handle on the upper carrier.
5. In a typewriting machine having a platen, in combination with feed-roll mechanism to feed a plurality of superposed groups of work-sheets interleaved with carbons successively or alternately around said platen, a set of carbon-carriers, each carrier being composed of a plurality of carbon-holding blades, said carriers being so arranged as to provide a space between adjacent carriers to permit the reverse threading therethrough of the forward portion of a lower group of work-sheets, and paper-guiding means so arranged as to afford an unobstructed drop located rearwardly of the carbon-carriers to receive said forward portion as the latter falls by gravity therein as said carriers are moved rearwardly during carbon stripping of the upper group of work-sheets, said drop preventing contact between the relatively moving groups of sheets.
6. In a machine of the class described having a platen and feed-roll mechanism to feed a plurality of superposed groups of work-sheets interleaved with carbons successively or alternately around said platen, the combination of a set of carbon-carriers, each carrier being composed of a plurality of carbon-holding blades, said carriers being so arranged as to provide a space between adjacent carriers to permit the reverse threading therethrough of the forward portion of a lower group of work-sheets, and

guide means for said groups of work-sheets located rearwardly of said carbon-carriers and including parallel transverse bars spaced both vertically and horizontally from each other, said bars defining a drop or chute to receive said reversely threaded forward portion and maintain the same out of contact with the upper group of sheets.

7. As a unitary structure, a plurality of superposed carbon-carriers, each composed of one or more carbon-holding blades, adjacent carriers being hingedly connected at one side.

8. As a unitary structure, a plurality of superposed carbon-carriers, each composed of one or more carbon-holding blades, adjacent carriers being so connected as to permit both tilting movement of an upper carrier with respect to a lower one and complete separation of the same.

9. In a typewriting machine of the class described having at the rear thereof a source of supply for a pair of work-webs, each web composed of a number of plies, and a bed-plate mounted for reciprocation at the rear of the platen and transversely thereto, a pair of superposed carbon-carriers having carbons arranged to be interleaved with the plies of the work-webs, the lower web when idle being tucked back in a loose reverse fold between the carbon-carriers, and anti-fouling means for preventing frictional contact between the upper web and the relatively moving reversely folded lower web during carbon-stripping of the upper web, said means including an unobstructed drop or chute of sufficient width to enable the free end of the reversely folded lower web to fall downwardly of its own weight without contacting the plies of said upper web, said carbon-carriers being detachable with their webs from said bed-plate and from each other for replacement with other carriers having different webs of forms, and the lower carrier being removable with its web rearwardly through said drop.

10. In a typewriting machine of the class described having at the rear thereof a source of supply for a pair of work-webs, each web composed of a number of plies, and a bed-plate mounted for reciprocation at the rear of the platen and transversely thereto, a pair of superposed carbon-carriers having carbons arranged to be interleaved with the plies of the work-webs, the lower web when idle being tucked back in a loose reverse fold between the carbon-carriers, and anti-fouling means for preventing frictional contact between the upper web and the relatively moving reversely folded lower web during carbon-stripping of the upper web, said means including an unobstructed drop or chute of sufficient width to enable the free end of the reversely folded lower web to fall downwardly of its own weight without con-

tacting the plies of said upper web, said drop or chute defined by horizontally and vertically spaced guide-bars over which the webs are directed from the source of supply to the carbon-carriers, said carbon-carriers being detachable with their webs from said bed-plate and from each other for replacement with other carriers having different webs of forms, and the lower carrier being removable with its web rearwardly through said drop.

11. In a typewriting machine of the class described having at the rear thereof a source of supply for a pair of work-webs, each web composed of a number of plies, and a bed-plate mounted for reciprocation at the rear of the platen and transversely thereto, a pair of superposed carbon-carriers having carbons arranged to be interleaved with the plies of the work-webs, the lower web when idle being tucked back in a loose reverse fold between the carbon-carriers, and anti-fouling means for preventing frictional contact between the upper web and the relatively moving reversely folded lower web during carbon-stripping of the upper web, said means including an unobstructed drop or chute of sufficient width to enable the free end of the reversely folded lower web to fall downwardly of its own weight without contacting the plies of said upper web, said carbon-carriers being detachable with their webs from said bed-plate and from each other for replacement with other carriers having different webs of forms and the lower carrier being removable with its web rearwardly through said drop, said upper carrier being also hingedly supported on said lower carrier whereby the former may be tilted away from the latter temporarily to increase the space therebetween to facilitate the rearward looping of the leading end of the idle lower web toward said drop.

12. In a typewriting machine of the class described having at the rear thereof a source of supply for a pair of work-webs, each web composed of a number of plies, and a bed-plate mounted for reciprocation at the rear of the platen and transversely thereto, a pair of superposed carbon-carriers having carbons arranged to be interleaved with the plies of the work-webs, the lower web when idle being tucked back in a loose reverse fold between the carbon-carriers, and anti-fouling means for preventing frictional contact between the upper web and the relatively moving reversely folded lower web

during carbon-stripping of the upper web, said means including an unobstructed drop or chute of sufficient width to enable the free end of the reversely folded lower web to fall downwardly of its own weight without contacting the plies of said upper web, said carbon-carriers being detachable with their webs from said bed-plate and from each other for replacement with other carriers having different webs of forms and the lower carrier being removable with its web rearwardly through said drop, said upper carrier being also hingedly supported on said lower carrier whereby the former may be tilted away from the latter temporarily to increase the space therebetween to facilitate the rearward looping of the leading end of the idle lower web toward said drop, said hinged support including hooked pins for releasably and pivotally connecting the upper carrier on the lower and also serving to locate it thereon.

13. In a typewriting machine of the class described having at the rear thereof a source of supply for a pair of work-webs, each web composed of a number of plies, and a bed-plate mounted for reciprocation at the rear of the platen and transversely thereto, a pair of superposed carbon-carriers having carbons arranged to be interleaved with the plies of the work-webs, the lower web when idle being tucked back in a loose reverse fold between the carbon-carriers, and anti-fouling means for preventing frictional contact between the upper web and the relatively moving reversely folded lower web during carbon-stripping of the upper web, said means including an unobstructed drop or chute of sufficient width to enable the free end of the reversely folded lower web to fall downwardly of its own weight without contacting the plies of said upper web, said carbon-carriers being detachable with their webs from said bed-plate and from each other for replacement with other carriers having different webs of forms and the lower carrier being removable with its web rearwardly through said drop, said upper carrier being also hingedly supported on said lower carrier whereby the former may be tilted away from the latter temporarily to increase the space therebetween to facilitate the rearward looping of the leading end of the idle lower web toward said drop.
